Attorney,

UNITED STATES PATENT OFFICE.

JOHN LE MAY, OF CHICAGO, ILLINOIS.

FLASH-LAMP.

SPECIFICATION forming part of Letters Patent No. 722,117, dated March 3, 1903.

Application filed July 25, 1902. Serial No. 117,038. (No model.)

To all whom it may concern:

Be it known that I, JOHN LE MAY, a citizen of the United States, residing at Chicago, in the county of Cook and State of Illinois, have invented certain new and useful Improvements 5 in Flash-Lamps, of which the following is a specification.

The object of this invention is to provide a device for holding and igniting flash-light 10 powders which will be safe, convenient to handle, inexpensive to manufacture, durable, and neat and which will ignite the powder by the explosion of a percussion-cap.

The object also is to provide a guard against 15 accidental explosion and to provide a device that can be readily taken apart for the purpose of cleaning.

I accomplish the objects of the invention by the mechanism illustrated in the accompanying 20 drawings, in which—

Figure 1 is a perspective view of my lamp with the powder-holder broken away in part; Fig. 2, a section longitudinally of the stem; Fig. 3, a detail of the upper end of the cylinder, showing perforations preliminary to the 25 formation of a fastening or lock therefrom; Fig. 4, a perspective view of same with the parts bent into operative position; Fig. 5, a detail in plan view of the powder-holder; and Fig. 6, a detail of the upper end of cylinder, 30 showing a modification in which the powder-pan is screwed upon the cylinder.

Like characters of reference indicate like parts throughout the several views of the 35 drawings.

Referring to the drawings, 7 represents a cylindrical body or stem, and 8 is a plunger having a close sliding fit therein. The movements of the plunger can be controlled from 40 the outside of the cylinder by means of the pin 9, which is seated in the plunger and extends to the outside of the cylinder through a slot 10 in the cylinder-wall. The length of this slot determines the play of the plunger. 45 Entering the lower portion of the slot is the catch 11, which in practice is the end of a spring-wire 12, which is bent in ample curvature around the cylinder in the manner shown in Fig. 1 and is then carried downwardly of 50 the cylinder and is secured by having its lower end 13 bent at right angles and projected through the cylinder through suitable

openings in both walls of the latter. The tension of the spring-wire is such as to force the catch 11 inwardly through the slot 10. 55 The plunger 8 has a notch 14 adjacent to its lower end. Below the notch the plunger is beveled, and the upper side of the catch 11 is beveled in order to produce an automatic locking device when the plunger is lowered 60 by outside pressure on the pin 9. A spring 15, seated on the end 13 of the spring 12, bears upwardly against the lower end of the plunger 8 and forces the latter suddenly and violently upward when the catch 11 is withdrawn. 65

A suitable pan to contain the charge of flash-light powder is secured to the upper end of the cylinder 7. This pan will preferably be long and narrow, as shown in Fig. 1, in order to produce a broad flat flame, which will 70 give more light for the same amount of powder than can be produced with a bowl or cup giving a round flame. I do not wish to confine my invention to the use of an elongated trough-like pan, however. The pan 15^a may be soldered 75 permanently to the end of the cylinder; but for convenience in cleaning the instrument and in making repairs I prefer to make the pan removable. In any case, however, a bridge spanning the mouth of the cylinder for the 80 plunger to press the cap against is required. This bridge 16 in the drawings is formed out of the flattened end of the cylinder, first perforated and slotted longitudinally, as shown in Fig. 3, and then bent, as shown in Fig. 4, in 85 which the side strips 17 17 are bent to form shoulders and the tongues 22 are bent out at right angles to the plane of the bridge. The bottom of the pan has a circular opening 18 with rectangular extensions 19 19 therefrom longitudinally of the pan. Through 90 these combined openings the bridge and shoulders 17 are projected until the contact of the tongues with the bottom of the pan arrests further progress. Then a quarter-turn of the 95 cylinder places the shoulders transversely of the pan and brings the tongues under the openings 19, closing the latter and causing the pan to be locked to the cylinder. A barb 20 will preferably be provided on the under 100 side of the bridge to make more certain the explosion of the cap 21, which is threaded between the bottom of the pan and the point of the barb, as shown in Fig. 2. The cap also

serves to close the mouth of the cylinder to keep the flash-light powder from dropping down therein. After the cap is in place the charge of powder is poured over it and is 5 properly distributed in the bottom of the pan.

While setting the plunger and after the plunger is set and until ready for the explosion, the stem should be grasped with the hand between the pin 9 and the pan, so that 10 the accidental release of the plunger will not cause a premature ignition, which will be prevented by the engagement of the pin against the hand, thereby preventing the contact of the plunger with the cap.

15 When ready to explode the charge, the lamp is held with the hand on the spring 12. This grasp compels the catch 11 to more closely hold the plunger until the catch is forced out of engagement by the pressure of the thumb 20 against the loop of the spring on the side opposite the catch.

Having thus fully described my invention, what I claim as new, and wish to secure by Letters Patent, is—

25 1. A flash-lamp consisting of a hollow cylindrical stem having a longitudinal slot, a charge-receiver carried by said stem, a bridge across the mouth of the stem, a plunger mounted in said stem, a pin seated in the plunger 30 and extending outside of the stem through said slot, means for normally urging the plunger toward the bridge and means for holding said plunger against the action of said urging means.

35 2. A flash-lamp consisting of a hollow cy-

lindrical stem having a longitudinal slot, a charge-receiver detachably secured to said stem, a bridge across the mouth of the hollow stem, a plunger mounted in said stem said plunger having an indent, a pin seated 40 in the plunger and extending through the slot to the outside of the stem, a spring-wire having its end passed through the stem and having a body portion carried thence toward the charge-receiver and terminating in a loop 45 around the stem the end of which loop enters the stem through the slot to form a catch to engage the indent in the plunger and a spring between the plunger and the spring-wire crossing said stem.

3. A flash-lamp consisting of a hollow cylindrical stem having its end flattened and its walls perforated and slotted and bent to form lateral locking tongues and shoulders, a charge-receiver having its bottom perforated and slotted to receive said end of the stem, a bridge across the mouth of the stem, a plunger mounted in said stem, a pin seated in the plunger and extending outside of the stem, means for normally urging the plunger 55 toward the bridge and means for holding said plunger against the action of said urging means.

In witness whereof I have hereunto set my hand and seal, at Indianapolis, Indiana, this 65 10th day of July, A. D. 1902.

JOHN LE MAY. [L. S.]
